UNITED STATES PATENT OFFICE.

CHARLES F. PAUL, OF CLINTON, ILLINOIS.

WATER-GAGE.

1,032,766.

Specification of Letters Patent. Patented July 16, 1912.

Application filed October 14, 1911. Serial No. 654,710.

To all whom it may concern:

Be it known that I, CHARLES F. PAUL, a citizen of the United States, residing at Clinton, in the county of DeWitt and State 5 of Illinois, have invented certain new and useful Improvements in Water-Gages, of which the following is a specification.

This invention relates to a compound safety water gage intended for use on locomotive and stationary boilers.

The invention consists in the novel features of construction, combination and arrangement of parts illustrated in the drawings and pointed out in the appended claim.

15 In the accompanying drawings:—Figure 1 is a side elevation of a water gage embodying my improvements. Fig. 2 is a central longitudinal section of Fig. 1. Fig. 3 is a fragmentary elevation of the upper half of 20 the gage. Fig. 4 is a sectional view of Fig. 3, and Figs. 5 and 6 are horizontal sections taken on the planes indicated by the dotted lines 5—5 and 6—6, respectively, of Fig. 3.

Referring to the drawings for a more particular description of the invention, the gage 25 comprises an inner glass tube 1 and an outer glass tube 2 which surrounds the inner tube and is of sufficiently larger diameter to provide the concentric space 3 therebetween. 30 The outer tube is incased in the metallic cylindrical casing 4 provided with four or more longitudinal openings 5. The casing 4 is exteriorly threaded at opposite ends, as at 6 and 7, for a screwed engagement with the interiorly threaded portions 8 of the caps 9. 35 The caps 9 are provided with the interiorly threaded outer portions 10 which are preferably of hexagonal form to facilitate the use of a wrench or other tool in screwing the 40 caps in place.

Packing rings or gaskets 10 are arranged between the ends of the metallic casing and shoulders 11 formed on the caps to provide a water tight joint between the 45 caps, casing and outer tube. The ends of the inner tube project beyond that of the outer tube and pass through corresponding apertures 12 in partitions 13 in the caps, whereby the inner tube is securely held in 50 a central position. The interiorly threaded

portion 10 of the bottom cap of the gage is intended to screw on the bottom water cock of the boiler, a packing ring 14 being disposed around the lower end of the inner tube to provide a water tight connection. The 55 lower exteriorly threaded end 15 of the hollow coupling sleeve 16 screws in the interiorly threaded portion of the top or upper cap of the gage against the packing ring 17. The upper end of the sleeve is also exteriorly threaded, as at 18, for a screwed connection with the steam pipe from the top of boiler. The sleeve is also preferably provided with a central hexagonal flange 19, to facilitate the use of a wrench in screwing 60 the sleeve in place. It will be understood that the outer glass tube acts as a guard and a protection from steam and water should the inner tube break, and also then serves the purpose of a water gage. 70

From the foregoing description taken in connection with the drawings, it is thought that the construction and advantages of this invention will be readily understood without requiring a more extended explanation. 75

Various changes in the form, proportions and minor details of construction may be resorted to without departing from the principles or sacrificing any of the advantages of this invention as defined in the 80 appended claim.

Having described my invention, what I claim as new and desire to secure by Letters Patent, is:—

85 A water gage of the class described comprising an inner glass tube, a second tube of larger diameter surrounding the inner tube, a metallic casing provided with a plurality of longitudinal openings, incasing the outer 90 tube, caps provided with interiorly threaded cylindrical inner portions formed with an annular interior shoulders and interiorly threaded reduced hexagonal outer portions, screwing on the ends of the casing, packing 95 rings between the shoulders of the caps and the ends of the casing, packing rings around the ends of the inner tube, perforated partitions formed in the caps for the reception of the ends of the inner tube whereby the 100

latter is supported in a central position said partition acting as a bearing for the packing rings and a hollow coupling sleeve screwing in the outer end of the top cap, 5 said coupling sleeve fitting and projecting beyond the upper end of the inner glass tube.

In testimony whereof I affix my signature in presence of two witnesses.

CHARLES F. PAUL.
